UNITED STATES PATENT OFFICE.

CHARLES FRANK SPAULDING, OF SALT LAKE CITY, UTAH.

APPARATUS FOR FLOTATION SEPARATION.

1,249,684.

Specification of Letters Patent. Patented Dec. 11, 1917.

Application filed February 11, 1916. Serial No. 77,658.

To all whom it may concern:

Be it known that I, CHARLES FRANK SPAULDING, a citizen of the United States of America, residing at Salt Lake City, county 5 of Salt Lake, State of Utah, have invented certain new and useful Improvements in Apparatus for Flotation Separation, of which the following is a full, clear, and concise description, reference being had 10 to the accompanying drawing, forming a part of this specification.

My invention relates to the flotation process of and apparatus for treating, concentrating and classifying mineral bearing ores 15 and sands by the use of oil, air and mechanical beating and has for its object to provide an improved process and apparatus for treating, concentrating and classifying mineral bearing ores and sands.

Further objects and advantages of this 20 invention are to materially reduce the cost and expense of present known processes of flotation treatment for mineral bearing ores and sands.

Further objects and advantages of this 25 invention are to improve and simplify the flotation process for mineral bearing ores and sands by providing for more accurate control of the amounts of oil and air admitted and used therein and of the mechanical beating thereof, substantially as described herein.

Further objects and advantages of this 30 invention are to allow and enable the user thereof to successfully treat, concentrate and classify mineral bearing ores not now amenable to any known process of flotation, due to the fullness and amplitude of the mechanical beating together with the use of oil 35 and air as hereinafter set forth.

In the accompanying drawings forming a part of this specification similar letters and numerals of reference designate corresponding parts throughout the two views.

In the drawings;

Figure 1 is a side view of an apparatus constructed in accordance with the invention, and

Fig. 2 is a sectional view thereof.

In carrying out the invention, I provide 50 a receptacle which may be divided into one or more cells 14, 15 and 16. Fig. 2 shows the arrangement of parts within one of these cells and by referring to this figure, it will 55 be seen that each cell contains an air lift column 1 in which beater arms 2 fastened

to vertical shafts 3 are located. Baffle plates 4 are located outwardly of the upper edge of the air lift columns and the lower edges of the baffle plates extend below the upper edges of said air lift columns. The upper edges of the air lift columns lie substantially in the plane of overflow lips 5. Discharge openings 6 provide for the passage of pulp from one cell to another when more than one cell is used or for drawing off the tailings when only one cell is used. An air inlet pipe 7 and an oil inlet pipe 8 communicate with an upturned nozzle which discharges into the lower end of the air lift column at 10. It is to be noted that the shafts carrying the beaters both rotate in the same direction and by providing a plurality of shafts, 3 equipped with beater arms, 2, and revolving these shafts in the same direction, the travel of the beater arms where they pass each other is in opposite directions. This not only gives a more effective beating action than could be secured with the use of one vertical shaft but 60 it prevents all tendency to set up a circular, whirling motion of the pulp, oil and air as it passes through the beater section of the air lift column and thereby obviates the necessity of providing baffle plates or other 65 devices which are necessary to break up or prevent such whirling motion when but one vertical shaft is so used. Since these beating arms are not designed to perform any lifting function or to aid in the circulation 70 of the pulp but, however, perform only the function of beating the pulp, oil and air to a froth, they may be of any suitable size or shape and may be numerous and small, whereby an efficient beating action is secured with less horse-power consumption 75 than in any known system of agitation. These beating arms are preferably located in an enlarged portion 9 of the air lift column 1, though this enlargement is not absolutely necessary, and in the use of the device 80 mineral bearing ores properly prepared by milling, crushing or grinding to the necessary fineness, or mineral bearing sands screened to the necessary fineness and mixed 85 with a sufficient amount of water to make a pulp of the required density is introduced into the first cell of the series, (where more than one cell is employed) through a feed pipe 11. Compressed air under sufficient 90 pressure to overcome the pressure of the pulp is introduced through pipe 8 into the 95

lower portion of the air lift column 1 by means of its connected nozzle and at a sufficient distance above the bottom of said air lift column so that the air will not back 5 down but will ascend therein. One of the functions of the air so introduced is to reduce the density or specific gravity of the pulp in said air lift column and this causes the pulp to circulate or rise in said column 10 due to the then difference between the weight or specific gravity of the pulp within the air lift column and that of the pulp within the remainder of the cell, the pulp thus circulating repeatedly, at the pleasure of the 15 operator, through the air lift column up past the beater arms 2 and out over the upper edge of the enlarged portions 9 of the air lift columns onto the main body of the pulp in the cell or receptacle so being treated, 20 where the concentration or classification takes place.

The froth which is caused by the action of the beater arms when oil and air are introduced through the pipes 7 and 8, respectively 25 and which froth contains the metals that are amenable to treatment, floats out of the cell over the overflow lips 5, the remainder of the pulp which is not beaten into a froth sinking into and mixing with the 30 main body of the pulp to again pass through the air lift column or through the opening 6 into the next cell if the cells are arranged in series as indicated in Fig. 1, and through the air lift column therein for 35 similar treatment. The pulp level in the cells is usually maintained several inches below the overflow lips 5 thus causing a clean froth to overflow and preventing the surging or waving of the pulp from slopping pulp over with the clean froth. 40

I prefer to introduce the oil for flotation at or near the bottom of the air lift column and with the air as indicated but it is to be understood that the oil can be introduced 45 separately and at any desired point. By introducing the oil and air in easily regulated amounts to each cell, a more efficient control of the frothing action is secured than by any known process of flotation. The amount and character of the oil admitted to each cell or receptacle can be so controlled as to give a selective action 50 on the metals in each cell.

I have found that the provision of a multiplicity of beating arms arranged as herein shown and described gives high efficiency to the flotation oils used due to the complete beating or agitation to which the oil, 55

air and pulp are subjected. I have found that in actual practice, I use less than one-tenth of the amount of oil used in other known processes of flotation for the same amount of oil and that the froth produced by my process is not a sticky and gummy mass but is a clean product which can be 60 handled as easily as the concentrates from a concentrating table.

Since each air lifting column 1 circulates the oil, air and pulp through or past the beater arms a number of times in each cell, the number of cells used in other processes of flotation may be materially reduced, thus reducing the floor space required for a given tonnage of ore handled and consequently materially reducing the first cost of installation over other known devices.

In the passage of the pulp, oil and air through an air lift column they are beaten to a froth which flows out of the top part of the air lift column and under the baffle plates 45 into the upper part of the cell, as hereinbefore set forth, the clean froth carrying the metals that are floated overflows at the overflow lips 5 as stated. The balance of the pulp and oil sinks into the main body of the pulp and into the bottom of the cell to be again passed through the air lift column except that that portion which is displaced by the incoming pulp passes to the next cell if there is more than one cell used.

While the elements shown and described are well adapted to serve the purpose for which they are intended, it is to be understood that the invention is not limited to the precise construction set forth but includes within its purview whatever changes fairly come within the spirit of the appended claim.

Having described my invention what I claim is:—

A device of the character described, comprising a pulp receiving cell, means for feeding material thereto, an air lift column disposed vertically therein, means for feeding compressed air and oil into the lower portion of said column and a plurality of vertical shafts arranged in said column, each of said shafts traveling in the same direction and a plurality of beater arms carried by each of said shafts.

In witness whereof I have hereunto set my hand in the presence of two witnesses.

CHARLES FRANK SPAULDING.

In the presence of—

P. C. ALLER,

R. D. MCPHAIL.
